UNITED STATES PATENT OFFICE

WALLACE W. RUSSELL, OF KANSAS CITY, MISSOURI

HIGHWAY GUARD RAIL

Application filed October 12, 1931. Serial No. 568,339.

This invention relates to improvements in highway guard rails, and more particularly to the resilient type of rail which will yield under impact and then spring back, thereby having a tendency to deflect the vehicle back onto the highway and also to absorb some of the force of the impact, and thus reduce the extent of damage done to a vehicle striking the same.

10 An important feature of my device is that the individual strips or rails are spaced outwardly towards the highway from the supporting posts and have shock absorbers or resilient members interposed between the 15 contact portion of the rail and the post. By this construction it is not necessary to use spring steel for the rail to give it the needed resilience and prevent its end from being mashed tightly against the post or deformed under the force of impact. This spacing from the post also prevents the hubs of the 20 vehicle wheels from contacting the post, thus reducing the possibility of broken wheels or axles, or damaged hubs and bent axles.

25 Another important feature is that adjacent ends of the rails are spaced apart and connected in such a manner that the rail sections can be individually tensioned. The 30 connections also permit the force of the impact to be absorbed in part by all of the sections as well as permitting the removal and replacement of an individual section without dismantling the entire guard rail.

35 Another important feature is that the adjacent ends of the rails are rounded so that no sharp pockets are present. This permits a vehicle to slide along the faces of the rails without becoming hung up in the space between adjacent sections because of the 40 rounded ends.

This invention is a continuation in part of my application for highway guard rail, filed September 8, 1931, Serial No. 561,521.

45 In accomplishing these and other objects of the invention, I have provided improved details of structure, the preferred forms of which are illustrated in the accompanying drawing, wherein:

50 Fig. 1 is a perspective view of a guard rail constructed according to my invention.

Fig. 2 is an enlarged fragmental top plan view of a portion of the rail with parts broken away and parts in section, showing the manner of connecting the ends of the rail together and of securing the sections to supports.

Fig. 3 is a fragmental disassembled perspective view of a section end and its associated parts.

Fig. 4 is a fragmental top plan view of a 60 pair of rail section ends showing a modified form of tensioning means.

Fig. 5 is a similar view showing a modified form of shock absorber.

Fig. 6 is a similar view showing a modified 65 form of rail section end.

Referring to the drawing in detail:

1 represents a highway guard rail which is composed of a number of rail sections 2 which are preferably strips of sheet metal 70 having the required tensile strength. At the ends of each section are reversely curved portions 3 and 4 forming laterally extending inner and outer sockets or pockets 5 and 6 facing in opposite directions, respectively. The end of the curved portion 4 is bent outwardly, forming a flange 7 which has bolt-receiving openings 8.

The curved portion 3 is provided with vertically aligned openings 9 through which tension means, to be explained later, extend.

An arcuate resilient shock absorber or member 10 is shaped to fit snugly in the pocket 5, and is provided with openings 11 so positioned and spaced as to register with the openings 9 when the guard rail is being assembled, and the shock absorber is preferably of a length equal to the width of the rail sections.

A thrust bar 12, having openings 13 which register with the openings 9 and 11, is preferably placed in the shock absorber 10 so as to distribute strains throughout the width of the sections.

The curved portions 4 may also be provided with openings 14 for the passage of securing means 15 so that the end sections can be secured to a support.

In erecting a guard rail having the sections formed as just described, supports 16, preferably wood, are first positioned at the 100

proper spacing. The rail sections are then placed in position with the supports 15 in the pockets 6 and bolts 17 passed through the openings 8. The shock absorbers 10 and bars

- 5 12 are placed in position and tension bolts 18 passed through the openings 9 of adjacent sections and the openings 11 and 13 of the shock absorbers 10 and bars 12, respectively; this will secure the rail sections to the intermediate supports. The outer ends of the end sections may be secured to the end supports by inserting the securing means 15 through the openings 14 and into the support.

- 15 A substantially V-shaped member or clevis 19 has its ends passed through the openings 9 of the outermost sections and also through the shock absorber 10 and bar 12, located in the sockets 5 of the end members and held therein by means of nuts 20. The eye 21 of 20 a guy or tension rod 22 is located in the crotch of the member 19, and the opposite end of the rod 22 is secured to an earth anchor or dead man. The guy rod 22 is preferably made of two sections connected by a turnbuckle 23 so 25 that it can be shortened and the entire guard rail be placed under an initial tension, the tension on the rail sections being regulated by the bolts 18.

30 Should the curved portions 3 of adjacent sections contact, they can readily be separated by loosening the bolts 18 and tightening up on the bolts 17.

35 In Fig. 4, I have disclosed a resilient tensioning device in which the bolt 24, which connects adjacent sections, is made longer, and a resilient sleeve such as a spring 25 is placed on the bolt and bears against the plates 12. By means of this resilient tensioning device, some of the impact between a vehicle 40 and a rail section is absorbed by the sleeve 25 and the shock absorber proportionately relieved of such shock.

45 The sleeves 25 may also be placed on the ends of the members 19 and the entire guard rail rendered more resilient.

50 In Fig. 5 I have shown the shock absorber 26 as being made of a block of rubber or similar resilient material fitted into the socket 5. In this construction the arcuate shock absorber 10 is eliminated, and the use of this type of shock absorber also serves to make a resilient tensioning device and takes the place of the sleeves 25 shown in Fig. 4. Plates 27 are used in connection with this type of shock absorber to prevent the heads and nuts on the tensioning bolts 28 from working into and through the shock absorber 26, as this would cause a slackening of the tension on the rail sections.

55 60 Fig. 6 shows a modified form of rail section in which the ends of a rail section 29 are laterally curved as at 30 to form a socket for the shock absorber. The curved portions are also provided with openings 31 through 65 which securing members 32 pass for securing

the sections to supports 33. Any of the shock absorbers and tensioning devices previously described may be used with this modified form of construction.

It will be noted that the rail sections are 70 arranged in spaced longitudinal alignment with each other so that while the rail can be initially tensioned by the guy rods, each section can be individually tensioned by the bolts connecting adjacent sections together. 75

What I claim and desire to secure by Letters Patent is:

1. In a highway guard including spaced supports and metallic rail sections, means for connecting the sections to each other and to 80 the supports including reversely curved ends on the rail sections forming laterally extending inner and outer curved portions, means for clamping the outer portions on the supports, and means for connecting the inner 85 portions of adjacent sections.

2. In a highway guard including spaced supports and metallic rail sections, means for connecting the sections to each other and to 90 the supports including reversely curved ends on the rail sections forming laterally extending inner and outer curved portions, means for clamping the outer portions in embraced condition on the supports, and adjustable means for connecting the inner 95 portions of adjacent sections.

3. In a highway guard including spaced supports and metallic rail sections, means for connecting the sections to each other and to 100 the supports including reversely curved ends on the rail sections forming laterally extending inner and outer socket portions, means for securing the outer portions to the supports, shock absorbers located in the inner 105 socket portions, and tensioning means extended through the shock absorbers and inner portions of adjacent sections for connecting the sections.

4. In a highway guard including spaced supports and metallic rail sections, means for 110 connecting the sections end to end and to the supports including curved end portions on the rail sections, means for securing the curved portions to the supports, resilient members adjacent the curved portions, and 115 means extended through the resilient members and said curved portions for connecting adjacent sections.

5. In a highway guard including spaced supports and metallic rail sections, means for 120 connecting the sections end to end and to the supports including curved end portions on the rail sections, means for securing the curved portions to the supports, resilient shock absorbers seated in the curved portions, 125 thrust bars adjacent the shock absorbers, and tensioning means extended through the thrust bars, shock absorbers and curved portions for connecting adjacent sections.

6. In a highway guard including spaced 130

supports and metallic rail sections, means for connecting the sections to each other and to the supports including reversely curved ends on the rail sections terminating in lateral flanges and forming laterally extending inner and outer curved portions, means for drawing the flanges of adjacent sections together to clamp the outer curved portions around the supports, and tensioning means extended through the inner curved portions of adjacent section for adjustably connecting the sections.

In testimony whereof I affix my signature.
WALLACE W. RUSSELL.
